UNITED STATES PATENT OFFICE.

JACOB R. SCOTT, OF NORTH WEYMOUTH, MASSACHUSETTS, ASSIGNOR TO UNITED SHOE MACHINERY COMPANY, OF PATERSON, NEW JERSEY, A CORPORATION OF NEW JERSEY.

SOLE-SEWING MACHINE.

1,233,513.

Specification of Letters Patent. Patented July 17, 1917.

Application filed October 13, 1913. Serial No. 794,858.

To all whom it may concern:

Be it known that I, JACOB R. SCOTT, a citizen of the United States, residing at North Weymouth, in the county of Norfolk and State of Massachusetts, have invented certain new and useful Improvements in Sole-Sewing Machines; and I do hereby declare the following to be a full, clear, and exact description of the invention, such as will enable others skilled in the art to which it appertains to make and use the same.

This invention relates to sole sewing machines, and more particularly to sole sewing machines of the McKay type.

In sole sewing machines of the McKay type the needle actuating mechanism is usually constructed and arranged to produce variations in the position of one of the limits of the needle stroke to correspond with changes in the thickness of the work so that the length of the loop drawn out by the needle above the work in the formation of each stitch will always be substantially the same, regardless of the thickness of the work. In McKay sole sewing machines at present in common commercial use, to produce the required variations in the needle stroke a needle actuating mechanism is provided in which there is lost motion between the needle bar and its actuating mechanism at the end of each stroke of the needle, which motion is terminated by limiting stops, the position of one of which is controlled by the vertical position of the presser foot as determined by the thickness of the work so as to vary the retracting stroke of the needle. In these machines a friction block is provided to engage the needle bar and the upward movement of the needle is arrested chiefly by the frictional resistance of the friction block. Considerable momentum is acquired by the moving parts during the retracting stroke of the needle and the action of the friction block is uncertain so that the needle often retracts beyond the normal limit of its upward stroke or overthrows, causing imperfect work, particularly when the machine is run at high speed.

The primary object of the present invention is to provide sole sewing machines of the McKay type with mechanism which will act with uniformity and certainty to arrest the movement of the needle in the direction

of its variable limit at substantially the normal limit of its stroke, regardless of the length of the stroke.

With the above objects in view, the invention comprises various novel features clearly set forth in the following description and pointed out in the claims, the advantages of which will be obvious to those skilled in the art from the following description.

In the drawings illustrating a machine embodying the invention in its preferred form;

Figure 1 is a view in front elevation of the machine; Fig. 2 is a view in side elevation of the machine looking from the left. Fig. 3 is a view in side elevation of the machine looking from the right; and Fig. 4 is a detail sectional view illustrating the presser bar and a portion of the mechanism by which it is actuated and controlled.

The machine illustrated in the drawings is a straight hook needle chain stitch sewing machine of the McKay type and comprises a vertically reciprocating straight hook needle 1, secured to the lower end of the needle bar 2, a cast-off 3, a presser foot 4 mounted on the lower end of the vertically movable presser bar 5 and a feed point 6. The work is supported during the sewing operation by a vertically fixed rotatable horn, the tip of which, shown at 7, contains a looping device for laying the thread in the hook of the needle. With the exception of the cast-off, the construction, arrangement and mode of operation of the parts above referred to and of the respective operating mechanisms for these parts in the machine illustrated in the drawings, are substantially the same as in the machine illustrated and described in the patent granted to the present applicant, No. 1,050,568, January 14, 1913. The cast-off is secured to the lower end of a bar 9 arranged in a groove in the needle bar which has a lateral projection 10 extending through a slot in a plate 11 and the bar is held in position with relation to the plate with the projection 10 at the lower end of the slot by a spring 12, the ends of which are engaged respectively in holes in the projection and plate. The plate 11 has a second slot 13 in which operates a lug 14 projecting from a block 15 attached to the needle bar. The cast-off is moved vertically by the engage-

105
110

ment of the lug 14 with the ends of the slot 13. The cast-off is held stationary during the first part of the stroke of the needle bar in each direction by a friction device 16.

5 The needle bar 2 is mounted to reciprocate vertically in guides in the upper and lower plates 17 and 18 of the head of the machine and is connected by means of a link 19 with the forward end of an actuating lever 20 pivoted on a stud 21 carried at the upper end of a fulcrum post 22. The lever 20 is oscillated about its fulcrum to reciprocate the needle by means of a crank 23 carried by the main shaft 24 of the machine 10 and connected with the rear end of the lever 20 by a pitman 25. The fulcrum post has a rising and falling movement between limiting stops which allows the needle to dwell respectively at the end of its stroke in each 15 direction. The stop which limits the upward movement of the fulcrum post is fixed so that the needle always descends to the same point during its downward stroke while the position of the stop which limits the 20 downward movement of the fulcrum post is controlled from the presser foot so that the upward stroke of the needle is varied as the work varies in thickness. The rising movement of the fulcrum post is limited by the 25 engagement of a clamp nut 26 threaded on the lower end of the post with the lower plate 18. The falling movement of the fulcrum post is limited by the engagement of the head of a screw bolt 27 carried by the 30 horizontal arm 28 of a sleeve 29 mounted on the fulcrum post with a stop 30 formed on a lever 31 pivoted at its rear end on the stud 32. The forward end of the lever 31 engages the upper face of a shoulder 33 on the 35 presser bar so that the vertical position of the lever and of the stop 30 is controlled by the vertical position of the presser foot. The sleeve 29 is held against the stop 34 fixed on the fulcrum post by a spring 35 coiled about the post and interposed between the sleeve and an adjustable clamp nut on the post. This spring allows the fulcrum post to yield downwardly just before the needle begins its upward stroke to obviate any sudden jerk upon the thread and to 40 prolong the dwell of the needle. A friction block 36 engages the needle bar and holds it stationary during the movements of the fulcrum post.

45 To prevent overthrow of the needle during its retracting stroke, in the construction illustrated, a block 37 is attached to the needle bar and extends rearwardly therefrom into position to engage the under side 50 of a block or slide 38 mounted to slide vertically on a vertical post 39 secured at its ends in the upper and lower plates of the head of the machine. The slide 38 is yieldingly pressed down by a coiled spring 40 surrounding the post 39 and interposed be-

tween the upper face of the slide and the plate 17. As the needle bar approaches the end of its normal upward stroke, the block 37 engages the lower face of the slide 38 and carries the slide upwardly therewith 70 against the resistance of the spring 40. The spring is thereby compressed and acts together with the friction of the friction block to check the upward movement of the needle bar immediately upon its release from 75 the action of its actuating mechanism. It is undesirable that the block 37 engage the slide 38 throughout any considerable portion of the upward stroke of the needle bar since when the slide is engaged and moved by the 80 block the force of the spring 40 furnishes considerable resistance to the upward movement of the needle bar. In order that the slide may be engaged by the block only during the last part of the upward stroke of 85 the needle bar and at substantially the same distance from the normal limit of upward stroke of said bar regardless of the height to which the needle bar moves, a rod 41 carried by the slide 38 is connected with the lever 31 by means of a screw pin 42, passing through a vertical slot 43 in the lower end of the rod. During each cycle of operations of the machine, the presser foot is lifted away from the horn to allow the work to be 90 fed as the needle is executing the latter part of its upward stroke. As the presser foot is lifted, the pin 42 strikes the upper end of the slot 43 and the slide 38 is lifted with the presser foot to a position such that the block 95 37 will engage the under side of the slide just before the needle reaches the normal limit of its upward stroke. The presser foot is lifted the same distance in each cycle of operation and the height to which it is 100 lifted varies with the thickness of the work so that the height to which the slide 38 is carried by the lifting of the presser foot varies with the thickness of the work and with the changes in the upward stroke of the 105 needle. The slide is therefore engaged by the block substantially the same distance from the end of the normal upward stroke of the needle whether the stroke of the 110 needle is relatively long or short.

115 The rod 41 is vertically adjustable in a bore in the slide 38 and is held in adjusted position in the slide by means of the nuts 44 threaded on the rod and engaging the upper and lower faces of the slide. By changing 120 the vertical position of the rod 41 with relation to the slide the point at which the block 37 engages the slide with relation to the limit of the normal upward stroke of the needle and the distance through which 125 the slide is moved by the block will be varied. The provision for adjustment of the rod, therefore, enables the action of the mechanism to be regulated so that the spring will furnish just the required resistance to 130

stop the upward movement of the needle bar at once upon its release from the action of its actuating mechanism.

It is obvious that if so desired the rod 41 5 may be so adjusted with relation to the slide 38 that the block 39 will engage the slide just as the needle reaches the limit of its normal upward stroke.

The presser bar 5 is mounted at its upper 10 and lower ends in suitable guides. The presser foot is held yieldingly in contact with the work by means of a spring 45 coiled about the presser bar and interposed between a fixed abutment and a collar 46 on the 15 presser bar. The downward movement of the presser bar when no work is in the machine is limited by an adjustable block 47 mounted on the upper end of the presser bar and arranged to engage a fixed abut- 20 ment 48. The mechanism for lifting the presser foot during each cycle of operations comprises a nut 49 mounted on the presser bar and engaging a series of screw threads 50 of steep pitch formed on the bar, a block 25 51 for engaging the nut to lock the nut from rotation on the presser bar, and mechanism for lifting the block to raise the nut and the presser bar. The nut when not engaged by the block 51 is free to turn on the 30 presser bar, so that it offers no resistance to the rising and falling movements of the bar. The nut is supported by an arm 52 projecting from a sleeve 53 mounted on a vertical rod 54 at the rear of the presser bar. A 35 spring 55 coiled around the rod and inter- posed between the upper end of the sleeve and a fixed abutment acts to force the sleeve downwardly. The downward movement of the sleeve under the force of the spring 55 40 is limited by an adjustable stop nut 56 mounted on the rod. The arm 52 supports the nut 49 by engaging in a groove in the nut, which groove is wide enough to permit a limited longitudinal movement of the nut 45 independent of the arm. The block 51 is mounted to slide freely on the presser bar below the nut and is provided with lateral projecting pins 57 upon which blocks 58 are mounted. These blocks are received in 50 slots in the forked forward end of an actuating lever 59 pivoted at 60 on the frame, the rear end of which is provided with a roll 61 engaging in a cam groove formed in a cam disk mounted on the main shaft 55 24. The upper end of the block 51 is formed with a slightly tapering friction surface 62 which is adapted to engage a corresponding friction surface 63 formed on the inside of the nut 49. When the 60 block 51 is raised it engages the nut 49 and lifts it independently of the arm 52 until the lower surface of the groove in the nut engages the arm. During this movement of the nut independent of the arm the pres- 65 sure of the engaging friction surfaces of

the block and the nut is slight and the nut rotates on the presser bar 5. During the continued upward movement of the block the arm 52 and the sleeve 53 are raised with the nut 49 and the spring 55 forces the friction surfaces together with a heavy pressure so that the nut is held from rotation and the presser bar is raised. The throw of the actuating lever 59 is uniform and inasmuch as the friction surfaces of the nut 70 and the block are always forced together with a heavy pressure at the same point in the upward movement of the block, and there is substantially no lost motion of rotation between the block and the nut thereafter, the presser foot is always lifted a certain and uniform distance. During the downward movement of the block 51 the presser bar is depressed by the action of the spring 45 and the nut is held in engagement 75 with the block by the spring 55 acting on the nut supporting sleeve 53 until the downward movement of the sleeve having been arrested by the stop nut 56, the upper surface of the groove in the nut engages the 80 arm 52, thereby arresting the downward movement of the nut, or until the presser foot engages the work. Then, as the block 51 continues its downward movement, the friction surface on the block is disengaged 85 from the corresponding friction surfaces on the nut, allowing the nut to turn freely on the presser bar, the presser foot then being held yieldingly in engagement with the work by the spring 45 and accommo- 90 dating itself to the thickness of the work. 95

Having explained the nature and object of the invention and having specifically described a machine embodying the same in its preferred form, what I claim is:—

105

1. A chain stitch sewing machine, having, in combination, stitch forming devices including a straight hook needle, a needle bar, mechanism for reciprocating the needle bar having a period of lost motion at the end of the stroke of the needle in each direction, means for varying the limit of the stroke of the needle in one direction as the work varies in thickness, a work support, a presser-foot, means independent of the needle mechanism for relatively moving the work support and presser-foot during each cycle of operations, a movable abutment for preventing overthrow of the needle bar during its movement in the direction of its variable limit, and means acting automatically to vary the position of said abutment in accordance with changes in the stroke of the needle.

110

2. A chain stitch sewing machine, having in combination, stitch forming devices including a straight hook needle, a needle bar, mechanism for reciprocating the needle bar having a period of lost motion at the end of each stroke of the needle, means for vary- 125

130

ing the limit of one of the strokes of the needle as the work varies in thickness, a work support, a presser-foot, means independent of the needle mechanism for relatively moving the work support and presser-foot during each cycle of operations, a movable yieldingly supported abutment for preventing overthrow of the needle bar during its stroke in the direction of its variable limit, and means acting automatically to vary the position of said abutment in accordance with changes in the stroke of the needle.

3. A chain stitch sewing machine, having, in combination, stitch forming devices including a straight hook needle, a needle bar, mechanism for reciprocating the needle bar having a period of lost motion at the limit of the retracting stroke of the needle, a vertically fixed work support, a vertically movable presser foot, means independent of the needle mechanism for lifting the presser-foot during each cycle of operations, means controlled by the work engaging position of the presser foot for varying the retracting stroke of the needle as the work varies in thickness, a movable abutment for preventing overthrow of the needle bar at the end of its retracting stroke, and a connection between said abutment and presser foot for varying the position of the abutment in accordance with changes in the retracting stroke of the needle.

4. A chain stitch sewing machine, having in combination, stitch forming devices including a straight hook needle, a needle bar, mechanism for reciprocating the needle bar having a period of lost motion at the end of the stroke of the needle in each direction, means for varying the limit of the stroke of the needle in one direction as the work varies in thickness, a work support, a presser-foot, means independent of the needle mechanism for relatively moving the work support and presser-foot during each cycle of operations, an abutment carried by one of the moving parts, a movable abutment for engagement with the first abutment during the stroke of the needle in the direction of its variable limit to prevent overthrow of the needle, means for varying the position of the second abutment at the time that the abutments are brought into engagement in accordance with changes in the stroke of the needle in the direction of its variable limit so that the abutments will be engaged through a uniform portion of the stroke of the needle, regardless of the length of the needle stroke.

5. A chain stitch sewing machine, having in combination, stitch forming devices including a straight hook needle, a needle bar, mechanism for reciprocating the needle bar having a period of lost motion at the limit of the stroke of the needle in each direction,

means for varying the limit of the stroke of the needle in one direction as the work varies in thickness, an abutment carried by one of the moving parts, a movable abutment for engagement with the first abutment 70 during the stroke of the needle in the direction of its variable limit to prevent overthrow of the needle, means for varying the point at which the abutments are engaged in accordance with changes in the stroke of 75 the needle in the direction of its variable limit so that the distance through which the abutments are engaged is constant, regardless of the length of the stroke of the needle, and provision for adjustment to vary 80 the point at which the abutments are engaged with relation to the normal limit of the needle stroke.

6. A chain stitch sewing machine, having in combination, stitch forming devices including a straight hook needle, a needle bar, mechanism for reciprocating the needle bar having a period of lost motion at the limit of the retracting stroke of the needle, a vertically fixed work support, a vertically mov- 85 able presser foot, means controlled by the work engaging position of the presser foot for varying the retracting stroke of the needle as the work varies in thickness, an abutment carried by one of the moving parts, a 90 movable yieldingly supported abutment for engagement with the first abutment to prevent overthrow of the needle bar at the end of its retracting stroke, a connection between said abutment and presser foot for varying 95 the position of the second abutment in accordance with changes in the retracting stroke of the needle bar so that the abutments will be brought into engagement at a constant distance from the normal limit 100 of the needle stroke regardless of the length of said stroke, and provision for adjustment to vary the point at which the abutments are brought into engagement with relation to the normal limit of the needle stroke. 110

7. A chain stitch sewing machine, having in combination, stitch forming devices including a straight hook needle, a needle bar, a work support, a presser foot, mechanism for reciprocating the needle bar having a 115 period of lost motion at the limit of the retracting stroke of the needle, a block carried by the needle bar, a vertically adjustable spring pressed block in the path of the first block to engage therewith and prevent 120 overthrow of the needle bar during its retracting stroke, a rod adjustably connected with the spring pressed block, and a connection between the lower end of the rod and the presser foot whereby the spring 125 pressed block is lifted as the presser foot is raised from the work.

8. A chain stitch sewing machine, having in combination, stitch forming devices including a straight hook needle, a needle 130

bar, mechanism for reciprocating the needle bar having a period of lost motion at the end of each stroke of the needle, means for varying the limit of the stroke of the needle in one direction as the work varies in thickness, a work support, a presser-foot, mechanism independent of the needle mechanism for relatively moving the work support and presser-foot during each cycle of operations, means inactive until the needle is adjacent the end of its stroke in the direction of its variable limit for arresting the movement of the needle bar, and mechanism for causing said means to act initially when the needle is at a constant distance from the limit of its stroke regardless of the length of the stroke.

9. A chain stitch sewing machine, having in combination, stitch forming devices including a straight hook needle, a needle bar, mechanism for reciprocating the needle bar having a period of lost motion at the end of each stroke of the needle, means for varying the limit of the stroke of the needle in one direction as the work varies in thickness, means inactive until the needle is adjacent the end of its stroke in the direction of its variable limit for arresting the movement of the needle bar, mechanism for caus-

ing said means to act initially when the needle is at a constant distance from the limit of its stroke regardless of the length of the stroke.

10. A chain stitch sewing machine, having, in combination, stitch forming devices including a straight hook needle, a needle bar mechanism for reciprocating the needle bar having a period of lost motion at the end of the stroke of the needle in each direction, means for varying the limit of the stroke of the needle in one direction as the work varies in thickness, a work support, a presser-foot, an abutment movable independently of the presser-foot for preventing the overthrow of the needle bar during the stroke of the needle in the direction of its variable limit and means acting automatically to vary the position of said abutment in accordance with changes in the stroke of the needle.
